HARROW CONSTRUCTION

Arnold E. W. Johnson, Chicago, Ill., assignor
to International Harvester Company, a corpora-
tion of New Jersey

Application August 12, 1938, Serial No. 224,431

10 Claims. (Cl. 55—83)

This invention relates to a harrow construction. More specifically, it relates to a disk harrow construction for use in orchard cultivation, comprising a pair of gangs pivotally connected and so constructed as to be turned either to the right or to the left.

In harrow constructions used in orchard cultivation, there is normally a pair of harrow gangs pivotally connected to one another. In working position, the gangs occupy an angle with respect to one another such that the harrow may be turned, for example, to the left, but not to the right. It is, therefore, necessary to provide some means for changing the angle of the gangs with respect to one another, so that the harrow may be turned to the right. It is desirable that this means be operative automatically upon turning of the tractor which pulls the harrow. It is to a construction of this type that the present invention is directed.

An object of the present invention is to provide an improved harrow construction.

Another object is the provision of an improved harrow construction comprising a pair of gangs pivotally attached to one another, which may be turned either to the right or to the left.

A further object is to provide, in a harrow construction comprising a pair of pivotally connected gangs, an arrangement for shifting the angle of the gangs to permit turning of the harrow in a certain direction where the angle of the gangs in working position does not permit turning in this direction.

Still another object of the invention is the provision in a harrow, having a pair of pivotally connected gangs and a connection from one end of the front gang to an offset member on the tractor pulling the harrow for pulling the end of the front gang around in turns, there being also a novel member for releasing the gangs from angled position when turns are to be made and for varying the angle of the gangs in working position.

According to the present invention, a pair of gangs are pivotally connected to one another. Draft means is connected to the right end of the front gang and to the left end of the rear gang. A chain connection is provided from a point adjacent the left end of the front gang to a bar offset laterally from a tractor pulling the harrow. A curved member is also provided and is releasably engageable at one end with the draft means for releasing the gangs from angle on turns and also releasably engageable adjacent the other end in a plurality of positions with the front gang for

varying the angle of the gangs in working position.

In the drawings,

Figure 1 is a plan view of the novel harrow construction in working position; 5

Figure 2 is an enlarged scale section taken along the line 2—2 of Figure 1;

Figure 3 is a section taken along the line 3—3 of Figure 1;

Figure 4 is a plan view of the harrow in transport position;

Figure 5 is an enlarged scale section taken along the line 5—5 of Figure 4; and,

Figure 6 is a plan view of the harrow when it is being turned to the right. 15

A harrow 10 comprises a front gang 11 and a rear gang 12 pivotally connected to one another by means of cross links 13 and 14. A transverse bar 15 is pivotally connected at 16 adjacent the right end of the front gang 11. At the other end 20

of the bar 15, a longitudinal reach bar 17 is connected, as at 18, and extends to a point of connection 19 on the left end of the rear gang 12. A U-shaped member 20 (Figure 5), secured to the front gang 11, holds down the reach bar 15. A 25

draft member 21, composed of adjustable sections 22 and 23, is pivotally attached at 24 to the right end of the gang 11. A draft member 26, also

composed of a pair of adjustable sections 27 and 28, is pivotally attached at 29 to a short piece 30 30

pivoted at the point 18 on the end of the bar 15. The two draft bars 21 and 26 extend forwardly to a point of connection 32, and the draft bar 26

extends beyond to a point of connection 33 with a U-bar 34 of a tractor, not shown. A bar 36 is 35

fixed to the U-bar 34 so as to extend laterally beyond and to receive in an opening 37 a chain 38 connected to a rod 39, in turn, connected to

mechanism on the front gang 11 of the harrow, to be described presently. 40

It will be noted that the bar 15 and draft bars 21 and 26 are connected substantially in tri-

angular form and constitute in effect a rigid draft applying means. The lengths of either the bars 21 or 26 may be varied by adjustment of the indi-

vidual sections, but for any one operation of the harrow the bars are kept fixed in length. 45

From this description it will be seen that draft is applied to the harrow from the tractor by

means of the draft applying means constituting 50

the bars 15, 21 and 26, and the reach bar 17.

Figure 1 shows the gangs in working position with the angle such that turns may be made to the left. However, it is necessary to transport

the tractor in some cases and, in others, to turn 55

it to the right. For these purposes the harrow is provided with a construction which will now be described. As seen in Figures 1, 4 and 6, a curved bar 42 is provided, which has at one end a notch 43 and, adjacent the other end, a series of notches 44. In the working position of Figure 1, the notch 43 at the front end of the bar 42 is so positioned as to be engaged by a member 46 (Figure 2) pivoted on a bracket member 47 secured 5 to a U-shaped member 48. The ends of the U-shaped member 48 support a bearing sleeve 49, which journals the bent end 50 of the reach bar 17. A rod 52 has one end secured to the U-shaped member 48 and its other end 53 bent at right angles and journaled in a bearing member 54 secured to the right end of the front gang 11 at the point previously referred to as 16. The U-shaped member 48 and the rod 52 constitute the individual parts of the bar 15 previously referred to. A retaining piece 56 is secured to the top of the U-shaped member 48, so as to enclose a space into which the curved bar 42 fits. As previously stated, the member 46 engages the notch 43 in the member 42 and is urged into this 10 position by a spring 57 between the member 46 and the base of the U-shaped member 48. This spring 57 surrounds a link 59 connected at one end to the member 46 and at the other end, as at 60, to one end of a lever 61 pivoted between 15 its ends in a sleeve 62 secured to the rod 52. A link 64 connects at 65 the other end of the lever 61 and one arm of a bell crank 67 journaled in a piece 68 secured to an angle member 69, forming part of the frame of the front gang 11. The bell crank 67 is also connected to the rod 39 previously referred to. It will be seen from this description that there is a connection established 20 between the laterally offset member 36 on the U-bar 34 of the tractor and the member 46 secured to the U-shaped member 48 of the bar 15 by means of the various links, levers and cranks, so that a pull by the member 36, resulting when the tractor turns to the right, is effective to swing the member 46 out of engagement with the notch 43 of the curved member 42, so as to release the 25 curved member from the bar 15.

As previously stated, there is a plurality of notches 44 adjacent the rear end of the curved member 42, and, in the working position shown in Figure 1, the next to the last notch 44 is engaged by the upstanding flange 70 of the angle member 69, the end of the curved member 42 passing through an opening in the flange 70. The curved member 42 is normally urged to the left, as viewed in the section of Figure 5, by means 30 of the parts shown therein, so that the flange 70 tends always to engage a notch 44 of the member 42, and the member 42 tends to be kept fixed with respect to the front gang 11. As seen in Figure 5, there is a loop member 71 surrounding the curved member 42 immediately behind the flange 70, the same being retained against the flange 70 by means of a vertical extension 72 and a channel 60 extension 73 secured to flange 70, in which channel extension 72 rides. An extension 74 at one side of the loop 71 is connected to a spring 75 connected, in turn, to a bolt 77 retained by a member 78 secured to one side of the front gang 11. A projection 80 extends from the other side of the loop 73 and 65 receives one end of a link 81, which has its other end connected to one arm of a bell crank 82 pivoted at 83 on the angle member 69. A cord or chain 84 is connected to the other end of the bell crank 82 and extends forwardly to within reach 70 of an operator's seat on the tractor. From this

description it will be seen that a forward pull on the cord 84 has the effect of pulling the loop 71 to the right, as viewed in Figure 5, so as to cause disengagement of a notch 44 from the flange 70. The spring 75 resists this movement and, when the cord is released, pulls the loop back, so that the flange 70 again engages a notch 44. 5

In operation, the gangs of the harrow occupy a position such as shown in Figure 1, the curved member 42 being fixed both to the front gang 11 and to the bar 15. Consequently, the gangs are held in one particular angle. It will be seen from Figure 1 that the gangs are in proper position to be turned to the left, since the intersection of the center lines of the harrow elements is to the left. 10 When, however, a turn to the right is to be made, a shifting of the harrow gangs is necessary. How this is accomplished will be seen from a comparison of Figures 1 and 6. As the turn is started, the tractor, including the draw-bar 34 and the laterally extending bar 36, is turned to the right. This means that the bar 36 swing away from the front gang 11. Consequently, a pull is transmitted through chain 38, rod 39, bell crank 67, links 59 and 64, and lever 61, to swing the member 46 out of engagement with the notch 43. This pull is also transmitted through the mounting of the bell crank 67 on the piece 68, so as to pull the left end of the front gang 11 forwardly. The forward end of the curved member 42, being released from bar 15 because of movement of the member 46 out of the notch 43 of the curved member 42, permits the front gang 11 to move forwardly to close the space between it and the bar 15. The gangs eventually move 15 into the position of Figure 6 with the center lines of the harrow elements intersecting at the right, so that the harrow itself may be turned to the right. When the tractor is again driven, straight pull is exerted on the harrow through point 33 and draft members 21 and 26, so as to move bar 15 away from gang 11 and bring the gangs back to the position of Figure 1. 20

When it is desired to change the angle of the gangs, for example, when they are to be brought 25 to transport position, a forward pull is exerted on the cord 84. This is effective to release the flange 70 of the angle member 69 from a notch 44 of the curved member 42. Then the tractor and harrow are backed until the gangs assume the parallel position of Figure 4. The curved member 42 has moved back through the flange 70. When 30 it is desired to move the gangs back to angled position, a forward pull is again exerted on the cord 84 and the harrow and tractor are driven forwardly until the proper angle of gangs is 35 reached. Then the cord 84 is released, and one of the notches 44 engages the flange 70, and the gangs are held in this particular angle. The gangs may be operated in any angle from parallel 40 transport position to the maximum angle of working position, by engagement of the flange 70 with the proper notch 44, which will hold the gangs in the particular angled position. 45

It will be seen from the foregoing description 50 that a new and novel harrow construction has been provided. The harrow is of the type in which a pull is exerted on one end of the front gang for bringing the gangs to proper position for turns. A separate member has been provided, 55 which has the double function of releasing the gangs from angle for turns and for allowing the variation of angle from parallel transport position to full angled working position. This member is, in a sense, floating and is free from a com- 60

plicated connection with the draft means or reach bar. Furthermore, the control members for varying the position of the gangs, namely, the cord 84 and the rod 39, are connected to the front 5 gang at positions away from the extreme ends of the gang. Consequently, there will be no interference with the operation of these parts by guard members placed over the ends of the front gang.

It will be apparent that changes may be made 10 in the above construction without departure from the spirit of the invention, and the intention is to limit the invention only by the terms of the appended claims.

What is claimed is:

15 1. In combination, a front harrow gang and a rear harrow gang movably connected to one another, a first link connected adjacent one end of the front gang, a second link connected at the opposite end of the rear gang and to the first 20 link at a point spaced from the point of connection of the first link to the front gang, third and fourth links extending from connections respectively with the aforesaid points to a common point of connection, a tractor, means connecting 25 the third and fourth links at the said common point and the tractor, an arcuate toothed member in generally parallel relation to the second link connected to the first link and to the front frame, flexible means extending from the front frame 30 to the tractor for releasing the arcuate member from the front frame, and means for releasing the arcuate member from the first link, said last means comprising a flexible member connected to the tractor at a point offset laterally from the 35 point of connection of the means connecting the tractor and the third and fourth links, and connecting pieces extending respectively along the first link from the arcuate member and along the front frame from the point of connection of 40 the flexible member.

2. In a harrow construction comprising front and rear gangs pivotally connected together, a first link connected to one end of the front gang, a second link connected to the other end 45 of the rear gang and to the first link, a tractor, draft means connecting the first link and the tractor, and flexible means connecting the tractor at a point offset laterally from the draft means and the front gang at a point toward the 50 opposite end from the point of connection of the first link to the front gang, the combination therewith of an arcuate member positioned in generally parallel relation to the second link on the side toward the center of the first gang and 55 releasably connected at one end with the front gang through flexible means extending within reach of an operator's seat on the tractor and at the other end with the first link, and means for releasing the arcuate member from the first 60 link by means of the first mentioned flexible means comprising a lever pivoted intermediate its ends on the first link adjacent its point of connection with the front gang, a first member extending along the first link and connecting one 65 end of the lever and the releasable connection of the arcuate member and the first link, and a second member extending along the front gang and connecting the other end of the lever and the first mentioned flexible means.

70 3. In a harrow construction comprising front and rear gangs movably connected to one another, a first bar pivotally connected to one end of the front frame, a second bar connected to the other end of the rear frame and to the first 75 bar, a draft means connected to the two bars, the

combination therewith of means for releasing the gangs from angled position for turns and for limiting the angled position of the gangs, said means comprising a bar releasably engageable adjacent one end with the frame and adjacent 5 the other end with the first bar.

4. In a harrow construction comprising front and rear harrow gangs movably connected to one another, and draft means connected to one end of the front gang and to the other end of the 10 rear gang, the combination therewith of a member releasably connected at one end to the draft means for releasing the gangs from angle for turns and releasably connected adjacent the other end to the front gang for limiting the angle 15 of the gangs.

5. In a harrow construction comprising front and rear gangs movably connected to one another, and draft means connected to one end of the front gang and to the opposite end of the 20 rear gang, the combination therewith of a member releasably connected at one end to the draft means and releasably connected adjacent the other end to the front gang, a first means connected to the front frame for releasing the member 25 to vary its position with respect to the front frame for varying the angle of the gangs, and a second means for releasing the member from the draft means to allow the gangs to move out of angled position for turns, said means comprising 30 a lever pivoted on the draft means adjacent the point of connection of the draft means with the front frame, a first link connecting one end of the lever and a release for the member on the draft means, and a second link extending from a point 35 of connection with the other end of the lever to a point substantially at the mid-section of the front gang.

6. In a harrow construction comprising front and rear gangs movably connected to one another, and draft means connected to one end of the front gang and to the other end of the rear gang, the combination therewith of a member for releasing the gangs from angle on turns and for varying the angle of the gangs in working position, said member being positioned on the front gang adjacent the end away from the end to which the draft means is attached and having one end notched for attachment to the draft means and having notches adjacent the other 50 end for attachment to the front frame.

7. In a harrow, front and rear gangs flexibly connected together, a draw frame structure pivotally connected to the front gang and adapted for connection to a tractor, said structure including a generally transverse bar having an end hinged to one end of the front gang, a generally longitudinal reach bar hinged to the other end of the transverse bar and spanning the front gang and hinged to the opposite end 55 of the rear gang, an arcuate bar, means releasably connecting one end of the last bar to the transverse bar, and means releasably connecting the other end of said last bar to the front gang.

8. In a harrow, front and rear gangs flexibly connected together, a draw frame structure pivotally connected to the front gang and adapted for connection to a tractor, said structure including a generally transverse bar having an end hinged to one end of the front gang, a generally longitudinal reach bar hinged to the other end of the transverse bar and spanning the front gang and hinged to the opposite end of the rear gang, latch means adjustably connected between said transverse bar and the front 70 75

end of the front gang whereby a turn in one direction of the tractor will trip the latch means, causing the open end of the front and rear gangs to close so that a turn may be made.

- 5 9. In a harrow, front and rear gangs flexibly connected together, a draw frame structure pivotally connected to the front gang and adapted for connection to a tractor, said structure including a generally transverse bar having an end hinged to one end of the front gang, a generally longitudinal reach bar hinged to the other end of the transverse bar and spanning the front gang and hingedly connected to the opposite end of the rear gang, a fore and aft extending arcuate bar, 10 means releasably latching the front part of the last bar to the transverse bar, means releasably latching the rear part of the arcuate bar to the

front gang, flexible means connected to the tractor and operative on a turn in one direction of the tractor to release the front part of the arcuate bar, and manually controlled means operable from the tractor to release the rear part 5 of the arcuate bar.

- 10 10. In a harrow, front and rear gangs flexibly connected to one another, draft means including a first bar connected to one end of the front gang, a second bar connected to the other end of the rear gang and to the first bar, and a member extending in generally closely spaced parallel relation to the second bar and being releasably engageable at one end with the first bar and at the other end with the front frame. 15

ARNOLD E. W. JOHNSON.
